ELIPHALET A. TRIPP, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR FEEDING NAILS.

1,132,638.

Specification of Letters Patent. Patented Mar. 23, 1915.

Application filed February 10, 1910. Serial No. 543,128.

To all whom it may concern:

Be it known that I, ELIPHALET A. TRIPP, a citizen of the United States, residing at Beverly, in the county of Essex and State 5 of Massachusetts, have invented certain Improvements in Machines for Feeding Nails, of which the following description, in connection with the accompanying drawings, is a specification, like reference characters 10 on the drawings indicating like parts in the several figures.

This invention relates to machines for feeding nails.

The machine herein set forth is adapted 15 for use with the heel nailing machine illustrated and described in United States Letters Patent No. 1,081,917, granted December 16, 1913. It will be understood, however, that machines embodying the present invention 20 could be used in connection with nailing machines other than that disclosed in said patent.

The machine shown is constructed for feeding headed nails as distinguished from 25 nails which are headless. As will be apparent from the following description, however, some of the features of the invention may be embodied advantageously in a machine for feeding headless nails.

30 The invention consists in the combinations of parts and features of construction hereinafter described and referred to in the appended claims.

In the drawings which illustrate a preferred embodiment of the invention,—Figure 1 is a view in perspective, with certain parts in section, of the machine; Fig. 2 is a view from the rear in Fig. 1 showing the actuating mechanism for the rotary hopper 40 and other parts hereinafter described; Fig. 3 is a view in perspective of a nail separator hereinafter referred to; Fig. 4 is a top plan view of the separator of Fig. 3 and a portion of the raceway with which said separator is combined; Fig. 5 is a view similar to Fig. 4 showing the separator in a different position; Fig. 6 is a view in vertical section of the lower end of a raceway and the nail tube leading therefrom; Fig. 7 is a view in 50 perspective of a portion of the nail transferrer hereinafter described.

Referring to the drawings and more par-

ticularly to Fig. 1, the reference numeral 1 indicates a casting suitably supported upon the frame of that machine with which the 55 nail feeding machine is combined. The casting 1 is provided upon its upper side with an inclined table in which is formed a series of raceways 4, six raceways being shown in the present machine. Each raceway 4 is formed 60 of two parallel plates vertically arranged in the casting and spaced apart to receive nails suspended by their heads between them. The raceway plates are separate from the casting 1 and the plates of each pair are 65 riveted together at a predetermined distance apart. The raceways are held in place in grooves formed in the casting 1 by means of screws 5 threaded in said casting and overlapping the upper edge of the raceway 70 plates. At the upper end of the raceways is mounted a rotary hopper 6 provided with vanes 8 upon its inner periphery forming nail pockets. The hopper 6 is secured to a shaft 7 mounted for rotary movement in the 75 casting 1 and rotated by mechanism hereinafter described. In its rotary movement the vanes 8 deposit nails upon the upper surface of the raceways, some of which enter the raceways and are suspended therein by their 80 heads. The hopper 6 is preferably removably secured upon the shaft 7 by means of a removable clamping wheel 9 threaded on the rear of the shaft 7.

In order to insure that the nails will be 85 properly positioned in the raceways there is provided a nail controller for each raceway which is constructed to adjust the nails in the raceway and to prevent nails which are improperly arranged from proceeding along 90 the raceway. To this end a cross piece 10 is secured to the casting 1, said cross piece having series of depending lugs 12 in which is journaled a shaft 14. Upon the shaft 14 is secured a series of controlling wheels 16 95 arranged above and closely adjacent to the respective raceways. Each wheel 16 is provided with a series of transverse peripheral notches forming teeth 18. Each tooth is grooved intermediate the sides of the wheel, 100 thus forming a circumferential groove about the wheel. The wheels 16 rotate in such a direction that their lower sides move up the raceway in a direction opposite to the move-

ment of the nails. In case a nail lies transversely across the raceway it is moved up the raceway by the teeth 18, and drops from the raceway back into the hopper. Such nails as are properly suspended in the raceway pass down the raceway through the grooves in the teeth 18. If nails in the raceway are too close together with their heads overlapping the teeth 18 shift them rearwardly.

At a point short of the lower end of each raceway there is mounted in the casting 1 a rotary nail separator disk 20. Each separator 20 is received in a circular recess in the casting 1 and provided with a depending central stud 22 received in a socket in said casting. An eccentrically arranged pin 24 extends upwardly from each separator. Each nail separating disk 20 is provided with a peripheral groove 26 which, as will appear from Fig. 3, is inclined relatively to the axis of the disk. The relation of a nail separating disk to its raceway is illustrated in Figs. 4 and 5 from which it will be apparent that by an oscillation of the disk between the limits shown in these two figures the lowermost nail above the separator will be separated from the rest of nails in the raceway, moved along the raceway under the influence of the separator and finally allowed to escape from the separator and proceed along the raceway. The nail separating disks 20 are arranged in a plane parallel with the upper faces of the raceway. The inclination of the groove 26 is provided on account of the fact that the lowermost nail above a separator is suspended in a substantially vertical position. The inclination of the groove 26 is such that in the nail receiving position of the separator as shown in Fig. 4 said groove is substantially vertical.

At the lower end of each raceway is provided an upwardly flaring nail receiving conduit 28 from which lead nail tubes 30. Each raceway is provided at its lower end with a transverse pin 32 arranged below the upper face of the raceway for the purpose of tilting the nail as it passes from the lower end of the raceway so that it will enter the nail tube 30 head first, as illustrated in Fig. 6.

The nail controllers 16 and the nail separators 20 are both actuated from the shaft 7 of the rotary hopper 6. To this end the shaft 7 projects forwardly beyond its bearing in the casting 1 and has mounted thereon a spiral gear 34 meshing with a similar gear 36 upon the shaft 14 of the nail controllers. The nail separators are interconnected by a connecting rod 38 having formed therein suitably spaced bores receiving the pins 24 of the nail controllers. A vertical lever 40 is pivotally supported intermediate its ends upon a pin 42 inserted in the casting 1. The lever 40 is provided at its lower end with a

longitudinal way for a slide block 44 having an outwardly extending pin entering a bore in the connecting rod 38. The upper end of the lever 40 is provided with a similar longitudinal way for receiving a slide block 46 in which is formed a bore to receive a pin 48 eccentrically located in the forward end of the shaft 7. It will be seen that in a single revolution of the shaft 7 the nail separators 20 will be given one oscillation. The nail controllers 16 will also be rotated an amount dependent upon the relative sizes of the gears 34 and 36.

For the purpose of securing access to the hopper and that portion of the raceways lying within the hopper, the front side of the hopper is provided with a door 50 hinged to lugs 52 projecting upwardly from the cross piece 10.

The nail tubes 30 lead to a nail foot 54 from which the nails are taken to the nail block of the nailing machine by a swinging nail transperrer 56. The nail transperrer 56 is secured to the lower end of a shaft 58 journaled in a vertical bearing in the casting 1. A spring 60 is arranged about the shaft 58, one end being secured to a collar 62 rigid with said shaft and the other end being secured to a stationary bushing 64 in which the shaft 58 is journaled. The spring 60 maintains the nail transperrer normally in position below the nail foot 54 and returns it to that position automatically after nails have been discharged from the transperrer to the nail block of the nailing machine. The nail transperrer is provided with nail passages for the reception of the nails from the foot 54 and has on its lower face beneath said passages a retaining plate 66 having perforations normally maintained out of line with the passages of the transperrer by a spring 68 co-operating with a stop 70 limiting movement of the retaining plate under the action of the spring. The retaining plate 66 is automatically moved to bring its apertures in alignment with the nail passages of the transperrer by engagement of a screw 72 upon said retaining plate with a part of the nailing machine proper.

In the machine shown, the rotary shaft 7 of the hopper 6 is actuated from the fly wheel 74 of the nailing machine. To this end there is provided a rotary shaft 76 having a disk 78 constructed for frictional engagement with the side of the fly wheel 74. This shaft is journaled at its lower end in a yoke 77, the lower forked end of which straddles the bearing for the shaft of the fly wheel 74. The yoke 77 is held yieldingly toward the fly wheel by a spring 79 and the disk 78 is thus pressed into yielding engagement with the side of the fly wheel. A manually operated cam 81 is indicated in Fig. 2 for the purpose of moving the friction wheel

78 out of contact with the fly wheel 74 and thus discontinuing the rotation of the shaft 76. The shaft 76 is provided at its upper end with a worm 80 formed to engage a 5 worm gear 82 secured to the rear face of the hopper 6. The shaft 76 is in continual rotation and is brought intermittently into operative relation to the gear 82. To this end said shaft 76 is journaled in a movable 10 sleeve 84, said sleeve being pivotally secured by a removable pin 86 to a horizontally movable supporting member 88. The supporting member 88 is held normally in the position shown in Fig. 2 by a spring 90 and said supporting member 88 is provided with a pin 92 arranged to be engaged by a latch 94 for holding said supporting member in that position in which the worm 80 is in engagement 15 with the gear 82. The hopper 6 is provided 20 with a cam 96 formed to engage the latch 94 and disengage it from the pin 90.

It will be seen that the mechanism described for actuating the hopper 6 insures a single rotation of said hopper whenever the 25 rotary shaft 76 is brought into operative relation to the gear 82. For the purpose of intermittently securing this relation between the shafts 76 and 7 the nail transferring shaft 58 carries at its upper end a lever 30 98 having adjustably mounted therein a set screw 100 arranged to engage a lateral extension 102 upon the sleeve 84. It will be seen that with this arrangement whenever the nail transerrer is brought into delivering 35 relation to the nail block of the nailing machine the shaft 76 will be moved to bring the worm on its upper end into mesh with the gear 82 on the shaft 7 of the rotary hopper, and will be held in that position by the 40 latch 94. The shaft 7 is thereupon given a single rotation at the end of which the latch 94 will be moved to allow the shaft 76 to be moved out of operative relation to the shaft 7. Nails may be supplied to the hopper 45 through the opening closed by the door 50. The hopper is emptied of nails by removing it from its supporting shaft. This may be done by removing the pin 86 and swinging the shaft 76 away from the hopper, removing 50 the clamping wheel 9 and thereafter removing the hopper longitudinally from the shaft 7.

Having described my invention, what I claim as new and desire to secure by Letters 55 Patent of the United States is:—

1. In a machine of the class described, a nail separator comprising a disk having in its periphery a groove both walls of which are inclined relatively to the axis of the 60 disk.

2. In a machine of the class described, a nail separator comprising a disk having in its periphery a groove inclined relatively to the axis of the disk, the disk being provided

with a depending central stud about which 65 the disk is movable circularly, and an upwardly extending eccentrically arranged pin by which the separator may be actuated.

3. In a machine of the class described, the combination with a plurality of raceways 70 formed to suspend nails by their heads, of a rotary hopper for supplying nails to said raceways, means for automatically rotating said hopper and means for discontinuing the movement of the hopper at the end of a 75 single rotation.

4. In a machine of the class described, the combination with a plurality of raceways formed to suspend nails by their heads, of a movable nail separator adjacent the lower 80 end of each raceway, a rotary hopper for supplying nails to the raceways, means connecting the hopper and separators whereby they move in unison, means for automatically rotating the hopper, and means for 85 discontinuing the movement of the hopper at the end of a single rotation.

5. In a machine of the class described, a raceway formed to support a series of nails, a hopper for supplying nails to said raceway, means for imparting a rotary movement to said hopper, an oscillatory separator in said raceway, and means directly connecting said hopper and said separator whereby rotary movement of the hopper is 95 translated into oscillatory movement of the separator.

6. In a machine of the class described, the combination with a plurality of parallel raceways formed to suspend nails by their 100 heads, of a rotary shaft arranged in parallel relation to the planes of the raceways, a hopper secured to said shaft and arranged to deliver nails to the raceways in its rotation, a rotary shaft arranged above the raceways and extending transversely thereof and provided with a series of nail controllers, means for transmitting movement from the first named shaft to the second shaft, a plurality of oscillatory nail separators 110 arranged adjacent to the lower ends of the raceways, a reciprocating rod connecting said nail separators for operating them in unison, and means for imparting to said rod a reciprocating movement from said first 115 named shaft.

7. In a machine of the class described, the combination of a nail raceway, a separator located to receive a nail from said raceway, nail driving means, a nail transerrer movable from a position to receive nails from said separator to a position to deliver said nails to said nail driving means, and means for starting the operation of said separator when said transerrer is moved to nail delivering position.

8. In a machine of the class described, a raceway comprising parallel rails for con-

veying nails, one of said rails having an opening, and a nail separator comprising a disk located with its periphery entering the opening in said rail and having in its periphery a groove inclined relatively to its axis.

In testimony whereof I have signed my

name to this specification in the presence of two subscribing witnesses.

ELIPHALET A. TRIPP.
